METAL DEACTIVATORS FOR HYDROCARBON OILS

Donald R. Stevens, Wilkinsburg, Pa., assignor to Gulf Research & Development Company, Pittsburgh, Pa., a corporation of Delaware

No Drawing. Application October 1, 1951,
Serial No. 249,215

18 Claims. (Cl. 44-63)

This invention relates to hydrocarbon compositions and methods for preparing the same.

Among the problems related to the field of hydrocarbon oils is that of oxidation and gum formation. Hydrocarbon oils such as gasoline, kerosene, diesel fuels, fuel oils, transformer oils, turbine oils, etc. undergo gum formation with a resultant adverse effect upon the marketability of the hydrocarbon oil. For example, the problem of gum formation assumes great importance in the field of gasoline fuels. Thus, when gum formation has occurred to any considerable extent, the value of the gasoline as a fuel for internal combustion engines is greatly reduced.

Gum formation is the result of the oxidation of unsaturated hydrocarbons which may be present in the hydrocarbon oil, and is effected from contact of the hydrocarbon oil with air. Such deleterious oxidation is most often encountered with gasolines, and in particular with cracked, reformed, and polymer gasolines which contain relatively high concentrations of monoolefins and somewhat smaller concentrations of other unsaturated hydrocarbons such as diolefins.

Accordingly, it is necessary to minimize or prevent the above-mentioned oxidation reactions. This has been accomplished by the addition to the hydrocarbon oils of so-called antioxidants or oxidation inhibitors. For example, antioxidants such as 2,6-di-t-butyl-4-methylphenol; 2,4,6-tri-t-butylphenol; hydroquinone; alpha-naphthol; bis(2-hydroxy-3-t-butyl-5-methyl-phenyl) methane; hardwood tar distillate; catechol; n-butyl-p-aminophenol; isobutyl-p-aminophenol; di-butyl-p-phenylene diamine; benzyl-p-aminophenol; di-benzyl-p-aminophenol; alpha-naphthylamine; 2-t-butyl-4-methoxyphenol; (Sustane); phenyl-alpha-naphthylamine have been added to gasolines.

In addition to the prevention of oxidation reactions, many hydrocarbon oils require some form of sweetening treatment for the conversion of mercaptans to organic sulfides, and/or removal of sulfur. This is particularly true in the case of gasolines. The sweetening treatment improves the odor of the gasoline and produces a product having a negative doctor test. The sodium plumbite or doctor process, as well as the hypochlorite sweetening process have been used for this purpose for many years. However, during recent years, the so-called copper-sweetening process has found wide use. In this process the gasoline is sweetened through contact with a copper-containing reagent such as cupric chloride. As a result of this treatment the sweetened gasoline usually contains small amounts of copper and/or copper compounds which have a catalytic effect on oxidation reactions such as gum formation. Because of the presence of the copper and its resultant catalytic effect on deleterious oxidation reactions the formation of gum is accelerated, and its yield increased over and beyond that which would otherwise occur in the gasoline.

Moreover, even hydrocarbon oils which have not undergone copper sweetening may contain gum-catalyzing metals and metallic compounds as the result of contact with such metals during the course of refining, storing, shipping, and usage operations. Thus the hydrocarbon oils may contain minute amounts of such metals as copper, iron, cobalt, nickel and the like and their compounds, which are oxidation catalysts.

The deleterious gum-catalyzing effect of the aforementioned metals cannot effectively be counteracted by the addition of conventional antioxidants. Thus, while in certain cases it is possible to add a sufficient amount of

2

an antioxidant to a gum-forming hydrocarbon oil to overcome the effect of a gum-catalyzing metal, the efficiency of the antioxidant under such conditions is so greatly diminished that very large amounts of it are necessary, and the advantage gained is seldom worth the cost of the increased quantity of antioxidant required. Moreover, while it is sometimes possible to remove the gum-catalyzing metal by purification, this is usually too costly to be practicable and is frequently impossible.

The present invention is directed towards stable hydrocarbon oil compositions in which the possibility of gum formation is obviated. Thus, the compositions of my invention comprise a hydrocarbon oil normally subject to catalyzed gum formation in the presence of a gum-catalyzing metal and additionally containing in an amount sufficient to suppress the gum-catalyzing effect of the gum-catalyzing metal a relatively minor amount of a compound having the formula:

wherein R represents a radical selected from the group consisting of hydrogen, alkyl, alkenyl, aryl, aralkyl and acyl radicals. In a preferred embodiment the compositions of my invention comprise a gum-forming gasoline containing a gum-catalyzing metal and additionally containing as a suppressor of the metal's gum-catalyzing effect a relatively minor amount of the afore-mentioned compound. This compound is effective as a metal deactivator in gasoline in very minor amounts, preferably of the order of 0.000003 weight per cent to 0.0015 weight per cent or about one-tenth to five pounds of metal deactivator per thousand barrels of gasoline. Furthermore, my invention also comprises the process for suppressing the effect of gum-catalyzing metals in gum-forming hydrocarbon oils, preferably in gum-forming gasolines. This is accomplished by incorporating a minor amount of the afore-mentioned type compound in the gum-forming hydrocarbon oil.

I shall illustrate the compositions and process of my invention by disclosing their application to gum-forming gasolines. However, it is to be understood that they are also applicable to other gum-forming hydrocarbon oils, such as those which have been mentioned heretofore. The gum-forming gasolines can be gasolines which, while normally relatively stable to oxidation, have been contaminated with a gum-catalyzing metal and rendered unstable. Gum formation in such gasolines can be retarded through the addition of metal deactivator without the addition of an antioxidant. Furthermore, the metal deactivators employed in accordance with my invention are advantageously added to metal catalyst-contaminated gasolines which contain conventional antioxidants. The presence of these antioxidants is desirable to prevent or minimize the oxidation which would normally occur even were the gum-catalyzing metal absent from the gasoline.

It is to be noted that the metal deactivators employed in the compositions of my invention have a different effect from that of conventional antioxidants. Thus, the antioxidant is especially effective for the deleterious oxidation reactions which normally occur; whereas the metal deactivators employed in my invention are specific suppressors of the gum-catalyzing effect of a gum-catalyzing metal which may be present. Were such a metal absent, the gasoline or other hydrocarbon oil would be rendered stable to air oxidation by the antioxidant. Accordingly, the metal deactivators employed in my invention are effective suppressors of the gum-catalyzing effect of metal catalysts in gasolines or other hydrocarbon oils where no antioxidant is employed; and also in gasolines or other hydrocarbon oils containing antioxidants. In the latter case, the metal deactivator renders it possible to effectively and economically stabilize the gasoline or other hydrocarbon oil by means of the antioxidant without employing the large amounts of antioxidant which would otherwise be necessary to overcome the catalytic action of the metal.

In this manner the metal deactivator increases the efficiency of the antioxidant.

The gasoline component employed in the preferred embodiment of my invention can be obtained from any of the sources employed for the derivation of gasolines. Thus, the gasoline may be straight run gasoline, natural gasoline, cracked gasoline, reformed gasoline, polymer gasoline or synthetic gasoline. Since the straight run and natural gasolines do not often contain appreciable quantities of gum-forming constituents, it is with the latter four types of gasoline that my invention is most useful. By "cracked gasoline" is meant gasoline obtained through the cracking or decomposition of higher boiling petroleum hydrocarbon fractions such as gas oil. By "reformed gasoline" is meant gasoline obtained from the isomerization and reforming of relatively low-boiling liquid hydrocarbons such as naphtha. By "polymer gasoline" is meant gasoline obtained from the polymerization of low-boiling hydrocarbons such as C₄ hydrocarbons. By "synthetic gasoline" is meant the gasoline obtained from the so-called "Fischer-Tropsch" synthesis in which gasoline is formed from the reaction between carbon monoxide and hydrogen. In addition to the afore-mentioned types of gasolines, gasolines from other sources such as the destructive hydrogenation of high-boiling hydrocarbon constituents like high-boiling liquid petroleum hydrocarbons, coal or lignite; and also gasolines obtained from shale sources can be used.

The finished gasoline compositions of my invention may also contain other additives such as antiknock additives like tetraethyl lead, dyes, etc.

The metal deactivators of the type herein involved comprise a compound having the formula:

wherein R represents a radical selected from the group consisting of:

(a) *Hydrogen*.—In this case the compound is kojic acid or 2-hydroxymethyl-5-hydroxy-1,4-pyrone.

(b) *Alkyl radicals*.—Preferably an alkyl radical having from 1 to 20 carbon atoms such as methyl, butyl, tertiary butyl, cyclopentyl, amyl, isoamyl, cyclohexyl, heptyl, octyl and cetyl.

(c) *Alkenyl radicals*.—Preferably an alkenyl radical having from 1 to 20 carbon atoms such as vinyl, allyl, 1-but enyl, 2-but enyl, 1,3-butadienyl, 1-pentenyl, 3-hexenyl, 2,4-hexadienyl, 2-octenyl, and 2-hexadecenyl.

(d) *Aryl radicals which may or may not contain alkyl substituents*.—Preferably an aryl radical having not more than 20 carbon atoms such as phenyl, diphenyl, naphthyl, tolyl, cumyl and duryl.

(e) *Aralkyl radicals*.—Preferably an aralkyl radical having not more than 20 carbon atoms such as benzyl, cumaryl, and α -mesityl.

(f) *Acyl radicals*.—Preferably an acyl radical having from 1 to 20 carbon atoms such as acetyl, caproyl, 2-ethylhexanoyl, lauroyl, stearoyl, oleoyl, benzoyl, cumoyl and the naphthenic acid type acyl radicals derived from naphthenic acids having a molecular weight of less than about 350.

Examples of these metal deactivators include kojic acid; 2-methoxymethyl - 5 - hydroxy-1,4-pyrone; 2-benzoyloxy-methyl-5-hydroxy-1,4-pyrone; 2-phenoxy-methyl - 5 - hydroxy - 1,4 - pyrone; 2-lauroyloxy-methyl-5-hydroxy-1,4-pyrone; 2-oleoyloxy-methyl - 5 - hydroxy - 1,4 - pyrone; 2-(2-ethylhexanoyloxy-methyl)-5-hydroxy-1,4-pyrone; the naphthenic esters of kojic acid wherein the naphthenic acid constituents have molecular weights of less than 350; 2-cumoyloxy-methyl-5-hydroxy-1,4-pyrone; and 2-benzoyl-oxymethyl-5-hydroxy-1,4-pyrone.

In order to show the effect of the metal deactivators of my invention on a gum-forming metal catalyst such as in the case of copper-catalyzed gum formation and oxidation in a copper-sweetened gasoline, the following examples are given:

Example I

A copper-sweetened gasoline stock derived from a mixture of straight run and catalytically cracked gasoline

from a mixture of crudes including Venezuela, Kuwait, and Mid-Continent crudes, and having the following inspection:

5	Doctor	-----	Good
	Sulfur, per cent	0.05	
	Copper dish gum, mg./100 cc., Method 330.12		
	Gov't. ¹	126	
10	Preformed gum, mg./100 cc., ASTM D381-46	1	
	Oxygen stability, 212° F., min. ASTM D525-46	165	
	Acid heat, ° F. ²	110	
	Copper, p. p. m.	0.31	
	Distillation, gasoline, ASTM D86-46:		
	Over point, ° F.	111	
15	End point, ° F.	367	
	10% evaporated at ° F.	132	
	50	204	
	90	305	
	Recovery, per cent	98	

20 ¹ Federal Specifications VV-L-791-D.
² The acid heat is determined by diluting 75 ml. of gasoline with 75 ml. of naphtha (the naphtha having an acid heat of less than 6.0) in a vented 250 ml. flask containing a Fahrenheit thermometer. 30 ml. of 93-95 per cent sulfuric acid are added to the mixture. The temperature of the mixture is noted as soon as the acid has been added. The flask is then shaken vigorously for 2 minutes. At the end of this shaking period, the temperature is noted again. The difference between the two temperatures is multiplied by 2, and the acid heat value for 150 ml. of the naphtha subtracted from this number. The remainder constitutes the acid heat of the gasoline in degrees Fahrenheit.

30 was employed as the gum-forming gasoline. A commercial gasoline antioxidant known as "Du Pont Antioxidant No. 22" which comprises N,N'-di-sec-butylphenylenediamine was added to the gasoline stock in a concentration of one pound per one thousand barrels, about 0.0003 weight per cent. This resulted in an improvement in the copper dish gum and oxygen stability characteristics of the mixture, these being:

35	Copper dish gum, mg./100 cc., Method 330.12,	25
40	Gov't.	225

Oxygen stability, 212° F., min. ASTM D525-46

45 Kojic acid was added in varying concentrations to the afore-mentioned copper-sweetened gasoline stock containing the antioxidant. The copper dish gum and oxygen stability characteristics of the resulting compositions are as follows:

50	Kojic acid concentration (lb./1,000 bbl. of gasoline stock)	0.25	0.50	1.0	2.0
	Copper Dish Gum, Mg./100 cc. Method 330.12,	18	8	6	5
	Oxygen Stability, 212° F., Min. ASTM D525-46	405	495	510	510

55 As can be seen from the foregoing, the addition of a minor amount of kojic acid resulted in a striking improvement in copper dish gum and oxygen stability characteristics for the gasoline composition, even though the gasoline contained a commercial antioxidant.

Example II
 The effect of the addition of 2-lauroyl-oxymethyl-5-hydroxy-1,4-pyrone on the copper dish gum and oxygen stability characteristics for the copper-sweetened gasoline containing Du Pont No. 22 antioxidant set forth in Example I is as follows:

70	2-lauroyloxy-methyl-5-hydroxy-1,4-pyrone (lb./1,000 bbl. gasoline)	0.25	0.50	1.0	2.0
	Copper Dish Gum, Mg./100 cc. Method 330.12,	18	17	6	6
	Oxygen Stability, 212° F., Min. ASTM D525-46	240	240	255	255

75 While the improvement in copper dish gum specifications for the compositions containing 2-lauroyloxy-methyl-5-hydroxy-1,4-pyrone is not quite as striking as that secured for the compositions containing kojic acid, these characteristics are markedly better than those obtained for the untreated mixture. Furthermore, the oxygen stability characteristics of the gasoline compositions containing 2-lauroyloxy-methyl-5-hydroxy-1,4-pyrone are somewhat better than the untreated mixture.

80 While the character of the invention has been described in detail and examples of the compositions given, this has been done by way of illustration only and with

the intention that no limitation should be imposed upon the invention thereby. It will be apparent to those skilled in the art that numerous modifications and variations of the illustrations and examples may be effected in the practice of the invention, and accordingly these modifications and variations should be construed as included within the scope of the claims appended hereto. Thus, as has previously been indicated, the description of the gasoline compositions and the processes for making the same set forth in my examples is to be regarded as merely illustrative, and the substitution of other hydrocarbon oils which are susceptible to gum formation in the presence of a gum-catalyzing metal is meant to be included. Furthermore, other gasolines having similar properties to those heretofore set forth can be utilized. In addition, other antioxidants, the use of which is readily apparent to one skilled in the art, can be substituted for those mentioned herein.

The compositions of my invention are possessed of superior oxidation stability and lowered gum-forming characteristics. Thus, in the case of gasolines, they comprise superior motor fuels.

In the appended claims, the expressions "gum-catalyzing metal" and "copper" are to be construed as meaning the gum-catalyzing metallic element such as nickel, iron, cobalt, or copper, and also as including gum-catalyzing compounds of said metals such as iron chloride, cupric chloride, etc., since even in such compounds it is the metallic component of the compound which catalyzes the gum formation.

I claim:

1. A composition comprising in combination a hydrocarbon oil normally subject to catalyzed gum formation in the presence of a gum-catalyzing metal and additionally containing in an amount sufficient to suppress the gum-catalyzing effect of the gum-catalyzing metal a relatively minor amount of a compound having the formula:

45

wherein R represents a radical having not more than 20 carbon atoms selected from the group consisting of hydrogen, alkyl, alkenyl, aryl, aralkyl, and acyl radicals.

2. A composition comprising in combination gum-forming gasoline containing a gum-catalyzing metal in an amount sufficient to have a catalytic effect on gum formation and additionally containing as a suppressor of said catalytic effect, a relatively minor amount of a compound having the formula:

60

wherein R represents a radical having not more than 20 carbon atoms selected from the group consisting of hydrogen, alkyl, alkenyl, aryl, aralkyl, and acyl radicals.

3. A composition comprising in combination gum-forming gasoline containing a gum-catalyzing metal in an amount sufficient to have a catalytic effect on gum formation and also containing about 0.00003 weight per cent to 0.0015 weight per cent of a compound having the formula:

75

wherein R represents a radical having not more than 20 carbon atoms selected from the group consisting of hydrogen, alkyl, alkenyl, aryl, aralkyl, and acyl radicals.

4. A composition comprising in combination gum-forming gasoline containing an amount of copper suffi-

cient to have a catalytic effect on gum formation and also containing, in an amount sufficient to be a suppressor of said catalytic effect, kojic acid.

5. A composition comprising in combination gum-forming gasoline containing an amount of copper sufficient to have a catalytic effect on gum formation and also containing, in an amount sufficient to be a suppressor of said catalytic effect, 2-lauroyloxymethyl-5-hydroxy-1,4-pyrone.

10 6. A composition comprising in combination gum-forming gasoline containing an amount of copper sufficient to have a catalytic effect on gum formation and also containing, in an amount sufficient to be a suppressor of said catalytic effect, 2-oleoyloxymethyl-5-hydroxy-1,4-pyrone.

15 7. A composition comprising in combination gum-forming gasoline containing an amount of copper sufficient to have a catalytic effect on gum formation and also containing, in an amount sufficient to be a suppressor of said catalytic effect, 2-(2-ethylhexanoyloxy-methyl)-5-hydroxy-1,4-pyrone.

20 8. A composition comprising in combination gum-forming gasoline containing an amount of copper sufficient to have a catalytic effect on gum formation and also containing, in an amount sufficient to be a suppressor of said catalytic effect, the naphthenic acid esters of kojic acid wherein the naphthenic acid constituents have molecular weights of less than 350.

25 9. A composition comprising in combination gum-forming gasoline containing an amount of copper sufficient to have a catalytic effect on gum formation and also containing about 0.00003 weight per cent to 0.0015 weight per cent of kojic acid.

30 10. The method for treating a hydrocarbon oil normally subject to catalyzed gum formation in the presence of a gum-catalyzing metal which comprises incorporating into said hydrocarbon oil in an amount sufficient to be a suppressor of the gum-catalyzing effect of the gum-catalyzing metal, a compound having the formula:

35 wherein R represents a radical having not more than 20 carbon atoms selected from the group consisting of hydrogen, alkyl, alkenyl, aryl, aralkyl, and acyl radicals.

40 11. A method for treating a gum-forming gasoline containing a gum-catalyzing metal in an amount sufficient to have a catalytic effect on gum formation which comprises incorporating into said gasoline in an amount sufficient to be a suppressor of said catalytic effect, a compound having the formula:

45 65 wherein R represents a radical having not more than 20 carbon atoms selected from the group consisting of hydrogen, alkyl, alkenyl, aryl, aralkyl, and acyl radicals.

70 12. A method for treating a gum-forming gasoline containing a metal in an amount sufficient to have a catalytic effect on gum formation which comprises incorporating into said gasoline about 0.00003 weight per cent to 0.0015 weight per cent of a compound having the formula:

75

80 wherein R represents a radical having not more than 20 carbon atoms selected from the group consisting of hydrogen, alkyl, alkenyl, aryl, aralkyl, and acyl radicals.

13. A method for treating a gum-forming gasoline containing an amount of copper sufficient to have a catalytic effect on gum formation which comprises incorporating into said gasoline in an amount sufficient to be a suppressor of said catalytic effect, kojic acid.

14. A method for treating a gum-forming gasoline containing an amount of copper sufficient to have a catalytic effect on gum formation which comprises incorporating into said gasoline, in an amount sufficient to be a suppressor of said catalytic effect, 2-lauroyloxy-methyl-5-hydroxy-1,4-pyrone.

15. A method for treating a gum-forming gasoline containing an amount of copper sufficient to have a catalytic effect on gum formation which comprises incorporating into said gasoline, in an amount sufficient to be a suppressor of said catalytic effect, 2-oleoyloxy-methyl-5-hydroxy-1,4-pyrone.

16. A method for treating a gum-forming gasoline containing an amount of copper sufficient to have a catalytic effect on gum formation which comprises incorporating into said gasoline, in an amount sufficient

to be a suppressor of said catalytic effect, 2-(2-ethylhexanoyloxyethyl)-5-hydroxy-1,4-pyrone.

17. A method for treating a gum-forming gasoline containing an amount of copper sufficient to have a catalytic effect on gum formation which comprises incorporating into said gasoline, in an amount sufficient to be a suppressor of said catalytic effect, the naphthenic acid esters of kojic acid wherein the naphthenic acid constituents have molecular weights of less than 10 350.

18. A method for treating a gum-forming gasoline containing an amount of copper sufficient to have a catalytic effect on gum formation which comprises incorporating into said gasoline about 0.00003 weight per 15 cent to 0.0015 weight per cent of kojic acid.
